UNITED STATES PATENT OFFICE.

DARWIN E. WISEMAN, OF MUNCIE, INDIANA, ASSIGNOR TO THE GLASCOCK BROS. MANUFACTURING COMPANY, OF SAME PLACE.

DESIGN FOR A KITCHEN-CABINET.

SPECIFICATION forming part of Design No. 29,887, dated December 27, 1898.

Application filed November 28, 1898. Serial No. 697,702. Term of patent 14 years.

To all whom it may concern:

Be it known that I, DARWIN E. WISEMAN, a citizen of the United States, residing at Muncie, in the county of Delaware and State of Indiana, have invented and produced a new and original Design for a Kitchen-Cabinet, of which the following is a specification.

This invention relates to a new and original design for a kitchen-cabinet; and it has for its object to provide a design of this character that shall be both useful and ornamental.

The leading features of the design reside in an upright cylindrical bin-body and a pair of vertical oblong rectangular drawer-casings projected or offset from the exterior of the bin-body respectively at opposite sides thereof and of a less height and width than the same.

While the essential or characteristic feature of the design resides in the cylindrical bin-body and the offset vertical rectangular drawer-casings at the opposite sides thereof, the design embodies several minor features—to wit, the cylindrical bin-body provided in its front side and at the lower end thereof with a rectangular drawer and the offset drawer-casings each provided with a series of vertically-aligned rectangular drawers exposed at the front side of the casing and each having a circular loop at its outer end.

In the drawings, Figure 1 is a perspective

view of a kitchen-cabinet embodying the herein-described design. Fig. 2 is a top plan view thereof.

Referring to the accompanying drawings, 35 the numeral 1 designates an upright cylindrical bin-body provided in its front side and at the lower end thereof with a rectangular drawer 2. The said body is also provided at diametrically opposite sides on the exterior 40 thereof with the oppositely-located vertical oblong drawer-casings 3. These drawer-casings extend upward from the bottom of the bin-body, but are of a less height and width than the body and are projected from the latter divergently with relation to each other, as shown in Fig. 2 of the drawings. Each of the offset drawer-casings 3 is provided with a series of vertically-aligned rectangular drawers 4, each having at its exposed front end a circular loop 5.

What is claimed is—

The design for a kitchen-cabinet, herein shown and described.

In testimony that I claim the foregoing as 55 my own I have hereto affixed my signature in the presence of two witnesses.

DARWIN E. WISEMAN.
